UNITED STATES PATENT OFFICE.

JAMES HALL TAYLOR, OF OAK PARK, ILLINOIS.

PROCESS OF MAKING NOZZLES.

Application filed November 28, 1924. Serial No. 752,526.

My invention relates to nozzles such as are commonly used in connection with steam boilers and the like, and contemplates a new and improved process of making them.

5 In the accompanying drawing the successive figures illustrate the successive steps in the process of my invention, although it will appear that the precise order of the steps, in the broader aspects of my invention, may be varied, and the appended claims have been drawn accordingly. The figures are all cross sectional views, with the exception of Figure 3, which is a plan view of the ingot in the form shown in Figure 2.

10 15 The billet of wrought metal, from which the nozzle is to be formed is shown at *a*. By the first step in the process this billet is heated and formed, by means of dies, into a circular body *b* having a flange *c*, at the bottom thereof, as shown in Figures 2 and 3, and a central depression *d* is formed in the top thereof. This depression *d* is formed as part of the step of providing a through central opening as will be clear 20 presently.

The next step in the process is to complete or form the through central opening *e*, as shown in Figure 4, this being accomplished by removing the metal below the depression *d* and sufficiently more to effect 25 a uniform diameter.

The next step in the process is to form the peripheral groove *f*, whereby an integral structure comprising an upper flange, a lower flange and a connecting neck is formed, as shown in Figure 5. This groove is preferably formed by inserting a mandrel in the opening *e* and applying rolling dies moving toward the axis as indicated by the 30 arrows, the billet being properly confined between upper and lower dies to insure the form of the flanges and the proper nozzle length. The groove *f* may also be formed by cutting in a lathe, in which event the 35 nozzle length is determined in the first instance, i. e., in the formation illustrated in Figure 2.

The last step in the process is to bend the lower flange into cylindrical form, as 40 shown in Figure 6, so that it may fit prop-

erly the boiler or the like to which it is to be secured.

I claim:

1. The process of forming nozzles which comprises first forming a circular body with a flange at one end and with a central opening of substantially ultimate size therethrough, and then forming a peripheral groove in said body adjacent said flange to form a central neck and a flange on the other end of said neck.

2. The process of forming nozzles which comprises forming a circular body with a flange at one end and with a central opening of substantially ultimate size therethrough, and rolling a peripheral groove in said body adjacent said flange to form a central neck and a flange on the other end of said neck.

3. The process of forming nozzles which comprises forming a circular body with a flange at one end and with a central opening of substantially ultimate size therethrough, forming a peripheral groove in said body adjacent said flange to form a central neck and a flange on the other end of said neck, and bending one of said flanges into cylindrical form.

4. The process of forming nozzles which comprises first forming a circular body with a flange at one end and with a central depression in the other end, then removing the metal in line with said depression to form a through central opening of substantially ultimate size, and then forming a peripheral groove in said body adjacent said flange to form a central neck and a flange on the other end of said neck.

5. The process of forming nozzles which comprises forming a circular body with a flange at one end and with a central opening of substantially ultimate size therethrough, rolling a fuller-shaped peripheral groove in said body adjacent said flange to form a central neck and a flange on the other end of said neck, and bending one of said flanges into cylindrical form.

In witness whereof, I hereunto subscribe my name this 18th day of November, 1924.

JAMES HALL TAYLOR.

CERTIFICATE OF CORRECTION.

Patent No. 1,680,073.

Granted August 7, 1928, to

JAMES HALL TAYLOR.

It is hereby certified that error appears in the printed specification of the above numbered patent requiring correction as follows: Page 1, lines 58, 66, 74 and 85, claims 1, 2, 3 and 4 respectively, before the word "peripheral" insert the compound word "fuller-shaped"; and the said Letters Patent should be read with these corrections therein that the same may conform to the record of the case in the Patent Office.

Signed and sealed this 23rd day of October, A. D. 1928.

(Seal)

**M. J. Moore,
Acting Commissioner of Patents.**
